UNITED STATES PATENT OFFICE

113,232

DESIGN FOR A COMBINED SINK AND FAUCET

Lee C. Love, Columbus, Ohio, assignor to The Ebcu Manufacturing Co., Columbus, Ohio, a corporation of Ohio

Application July 22, 1938, Serial No. 78,648

Term of patent 7 years

To all whom it may concern:

Be it known that I, Lee C. Love, a citizen of the United States and a resident of the city of Columbus, in the county of Franklin and State of Ohio, have invented a new, original, and ornamental Design for a Combined Sink and Faucet, of which the following is a specification, reference being had to the accompanying drawing, forming part thereof.

The figure is a perspective view of a combined sink and faucet showing my new design.

I claim:

The ornamental design for a combined sink and faucet, as shown.

LEE C. LOVE.
